CHARM BRACELET

George Plotkin, 233 Broadway, New York, N.Y.

Filed Aug. 16, 1960, Ser. No. 61,774

Term of patent 3½ years

(Cl. D45—4)

FIG. 1 is a perspective view of a charm bracelet, showing my new design;

FIG. 2 is a rear elevational view thereof;

FIG. 3 is a right side view thereof on a reduced scale; and

FIG. 4 is a top plan view thereof.

The essential features of my design reside in the portions shown in full lines.

This application is a continuation-in-part of patent application D. 59,037 filed January 13, 1960.

I claim:

The ornamental design for a charm bracelet, as shown and described.
